DESIGN FOR A BOTTLE

Otto Seidner, Westerly, R. I., assignor to Otto Seidner, Inc., Westerly, R. I., a corporation of Rhode Island

Application July 16, 1934, Serial No. 52,603

Term of patent 14 years

To all whom it may concern:

Be it known that I, OTTO SEIDNER, a citizen of the United States, residing at Westerly, in the county of Washington, State of Rhode Island, have invented a new, original, and ornamental Design for a Bottle, of which the following is a specification, reference being had to the accompanying drawing, forming a part thereof.

Fig. 1 is an elevational view of the bottle of my design;

Fig. 2 is an elevational view thereof looking at the bottle from the left side of Fig. 1; and

Fig. 3 is a fragmentary vertical sectional view through the bottom portion thereof.

I claim:

The ornamental design for a bottle as shown.

OTTO SEIDNER.
